SEALED PACKAGE

Walter K. Berthold, Rockville, Conn., assignor to
Hartford-Empire Company, Hartford, Conn., a
corporation of Delaware

Application May 21, 1943, Serial No. 487,892

4 Claims. (Cl. 215—40)

This invention relates generally to improvements in sealed packages. It relates more particularly to a sealed package of the type which comprises a glass container, a cap closure for the container and a gasket of compressible, resilient material pressed between lateral surfaces of the container and the cap to provide a hermetic seal.

An object of the invention is to provide an improved sealed package of the character described wherein the closure cap can be quickly and easily applied to the container to cooperate therewith and with a sealing gasket to provide an effective hermetic seal, will be securely retained in place to maintain such seal even though subjected to substantial shocks, jars and internal pressure, and can be quickly and easily removed when opening of the package is desired.

A further object of the invention is to provide a sealed package of the character described wherein the same closure cap and gasket may be used repeatedly to close and seal the glass container, being readily removable in reusable condition and replaceable at will.

A sealed package provided in accordance with the present invention may comprise a glass jar or other glass container formed with an external annular sealing surface thereon adjacent to the mouth of the container. A cap closure for the container has a cooperative internal annular sealing surface formed on a skirt portion of the cap in position to encircle the sealing surface on the container in spaced concentric relation therewith when the cap has been applied to the container. The annular sealing surface on the container may decrease in diameter from the end portion thereof nearest to the mouth of the container toward its opposite end and thus may be said to be of inverted frusto-conical or downwardly tapering shape. The cooperative annular sealing surface on the skirt portion of the cap closure may be cylindrical in shape.

The gasket may be an endless ring of rubber or some rubber-like or other compressible and resilient material. The ring may be of rectangular cross-section, and is of sufficient inner and outer diameters to be pressed between the two cooperative sealing surfaces to provide an effective hermetic seal when the cap has been pressed onto the container. The construction and arrangement are such that any pressure tending to move the cap axially from its applied position will be resisted not only by the friction between the contacting surfaces of the gasket and of the container and skirt of the closure, respectively, but by a wedging action exerted by the relatively

less compressed or fully expanded portion of the gasket which is located in the wider end portion of the annular space between the cooperative concentric sealing surfaces. In consequence, any pressure, internal or otherwise, tending to lift or force the cap axially from the container will be firmly resisted. The cap can be readily pried off the container, however, because it then is swung pivotally at one side against a portion of the gasket as a fulcrum at the opposite side of the container.

Other objects and advantages of the invention will hereinafter be pointed out or will become apparent from the following description of an illustrative embodiment of the invention, as shown in the accompanying drawing, in which:

Fig. 1 is a fragmentary view, partly in elevation and partly in vertical section, showing the upper end portion of one form of sealed package embodying the invention, the frusto-conical sealing surface being on the container;

Fig. 2 is a fragmentary vertical sectional view to illustrate the relative positions of the open end or neck finish portion of the container, the gasket, and the cap at the beginning of the operation of pressing on the cap to form the sealed package of Fig. 1;

Fig. 3, 4, 5 and 6 are views like Fig. 2 but respectively showing the relative positions of the parts at successive stages in the operation of applying the cap to the container, such cap being in fully applied position in Fig. 6;

Fig. 7 is a fragmentary vertical section of the sealed package of Figs. 1 and 6 but illustrating the wedging action of the gasket in resisting internal pressure tending to move the cap axially from the container;

Fig. 8 is a fragmentary vertical sectional view of the package shown in Figs. 1 and 6, illustrating the operation of prying the cap from the container.

The sealed package shown in Figs. 1, 6, 7 and 8 comprises a glass container 1, specifically a jar. This jar may have been formed in any suitable known manner by any suitable known machine. The open end or neck finish portion 2 of the jar has been formed with an external annular inverted frusto-conical sealing surface 3 thereon adjacent to the end surface 4 at the mouth of the jar. The inverted frusto-conical surface 3 is of greater diameter at its end nearest to the mouth of the jar than at its opposite end. At its larger end, the inverted frusto-conical surface 3 may be merged into the end surface 4 by a rounded corner surface 5. The juncture of the

larger end of the surface 3 and end surface 4 might be effected by any other suitably shaped connecting surface. At its lower or smaller end, the inverted frusto-conical surface 3 is merged into an outwardly and downwardly inclined surface 6, constituting the upper surface of an external flange or bead 7 on the neck of the jar. At a predetermined distance below the flange 7, the jar is enlarged to form the body thereof, thus providing a shoulder 8. This shoulder 8 may serve as a rest for a cap pry-off implement, as hereinafter will be pointed out.

The cap closure which is adapted to cooperate with the jar 1 may be made of glass. It may comprise a cover or head portion 9 and a depending annular rim flange or skirt 10. The head or cover portion 9 may have its central part 9a depressed so as to depend into the neck portion of the jar while leaving an annular clearance space 11 between the end surface 4 at the mouth of the jar and the overlying portion of the cap when the latter is in applied position. The inner wall of the skirt of the cap is formed to provide a cylindrical sealing surface 12 extending from the juncture of the skirt and the head or cover portion of the cap for a sufficient part of the length of the skirt to cooperate effectively with the inverted frusto-conical surface 3 on the neck of the jar when the cap is in applied position. The surface 12 may merge at its lower end into a downwardly enlarging inclined guiding surface 13 extending past the flange 7 on the neck of the jar. The skirt of the cap may be of sufficient length to extend nearly but not quite to the shoulder 8 of the jar.

The surface 12 preferably is merged at its upper end into the lower surface of the head or cover portion of the cap by an arcuately curved or rounded surface at the inner corner of the cap, as indicated at 12a.

The diameter of the cylindrical sealing surface 12 is sufficiently greater than the diameter of the larger upper end of the inverted frusto-conical sealing surface 3 on the neck of the jar to cause these surfaces to define between them an annular space in which a gasket 14 may be partially compressed and distorted when the cap is in applied position.

This gasket compression space is narrowest between the upper end of the sealing surface 3 and the directly encircling portion of the surface 12. It is partially closed at its bottom by the surface 6 of the flange 7 on the neck of the jar. The gasket 14 is a ring of rubber or rubber-like material, preferably of rectangular cross-section when in its expanded or pressure-free condition. The inner diameter of gasket preferably is about that of the diameter of the smallest end of the inverted frusto-conical sealing surface 3 and thus is slightly smaller in diameter than the upper larger-diameter end of such inverted frusto-conical surface. The outer diameter of the gasket is slightly more than the diameter of the cylindrical sealing surface 12 on the inner wall of the skirt of the cap. The height of the gasket ring, in the embodiment of the invention shown in Figs. 1, 6, 7 and 8, is slightly greater than the vertical distance between the surface 6 on the flange 7 of the neck of the jar and the level of the upper end surface 4 at the mouth of the jar.

The operation of applying and sealing the cap 9-10 onto the jar 1 to form a sealed package substantially as just described is illustrated as successive stages in Figs. 2 to 6, inclusive.

As shown in Fig. 2, the gasket 14 has been

placed on the external inverted frusto-conical sealing surface 3 of the jar. The cap skirt is being telescoped over the projecting upper portion of the gasket 14. At this time, the contact of the cap with the gasket is mainly between the upper outer corner 15 of the gasket and the guiding surface 13 of the skirt of the cap and the gasket has not yet been forced downwardly against its seat on the surface 6 at the top of the flange 7. Such compression and distortion of the gasket as occur at this stage are in a direction generally diagonal of the gasket from its upper outer corner toward its lower inner corner.

Further movement of the cap downwardly toward its applied position will compress the gasket between the upper part of the inverted frusto-conical surface 3 and the downwardly moving guiding surface 13 of the skirt of the cap in the heavily stippled portion 16, as shown in Fig. 3. This compression is exerted in a generally downward and inwardly inclined direction with relation to the vertical central line of the jar and is attended by a slight distortion of the gasket, as shown, after the latter has been forced against its seat on the surface 6 of the flange 7.

When the cap has progressed downwardly in its movement onto the jar to the position shown in Fig. 4, the compression of the gasket will be mainly throughout the intermediate portion thereof indicated by the heavy stippling at 17 in Fig. 4.

By the time the cap reaches the position illustrated in Fig. 5, the cylindrical gasket sealing surface 12 has in part had sliding contact with the outer surface of the gasket and has compressed a substantial portion of the gasket, extending from near the upper end thereof for more than half its length between itself and the cooperative sealing surface 3, as indicated by the heavy stippling 18. The gasket has been distorted so that it is slightly narrower at its intermediate portion than at its lower part and extreme upper end.

Fig. 6 shows the cap in its fully applied position. At this time, an upper portion of the gasket is compressed between the diagonally aligned corner surfaces at the rim of the jar and the inner wall of the cap, respectively, as indicated at 19. The curvature of the inner corner surface 12a of the cap aids in biasing the upper end portion 19 of the gasket to the position shown as the cap is applied. The lower end portion of the gasket is in a less compressed condition as indicated at 20 in the wider lower portion of the space between the cooperative surfaces 3 and 12. The intermediate portion of the gasket is under greatest compression between the upper part of the sealing surface 3 and the directly outlying part of the cooperative sealing surface 12, as indicated at 21.

It will be noted that there is no appreciable resistance to the cap in its movement toward its applied or pressed-on position until the cap has accomplished a substantial part of its guided movement relative to the jar toward that position. Resistance to further movement of the cap as it is being pressed onto the jar will increase and attain a maximum when the cap arrives at its fully pressed-on or applied position. The cap thus may be quickly, easily and accurately applied simply by pressing it onto the jar in telescopic relation to the gasket on the latter. If desired, the gasket may be wetted to facilitate the application of the cap.

The cap of the sealed package described will be held securely in place on the jar. Should

internal pressure tend to move the cap axially from the jar, as in the direction indicated by the arrows 22 in Fig. 7, the pressure will be resisted along the lines indicated by the heavy stippling at 23 in Fig. 7. An exaggerated yielding to such pressure while the cap is still secured in place is indicated in Fig. 7 in order better to illustrate the action. The friction between the glass of the cap and the gasket is greater than that between the glass of the jar and the gasket. The gasket thus will tend to move upward with the cap. This and consequently upward movement of the cap will be resisted by the more expanded lower portion of the gasket, which must be compressed radially before it can move through the narrower space between the upper part of the inverted frustoconical sealing surface 3 and the cylindrical sealing surface 12. Internal pressures of as much as 16 pounds per sq. in. have been successfully resisted by hermetic seals of the invention like that just described.

The cap can be removed readily from the jar, when desired. As shown in Fig. 8, a suitable implement 24, which may be a spoon handle or the like, has been placed on the shoulder 8 beneath an edge of the skirt of the cap and is being manipulated as a lever to pry off the cap. The cap then will swing on the lower portion, indicated at 25, of the gasket at the side of the jar opposite the lever. This will tend to relieve the compression on the portion of the gasket above the lever, as indicated at 26, so that the cap may be quickly and easily pried off, leaving the gasket in substantially its original condition. The cap therefore may be readily replaced on the container and the seal again established.

A feature of advantage of the sealed packages of the invention is that the sealing action of the gasket is such and is so produced that compressible material of considerably lower grade than high grade rubber may be used to provide an effective seal, particularly under certain conditions. In packages of the present invention wherein a partial vacuum exists in the container, gasket materials may be used which become quite plastic and lose most, if not all, of their elasticity at comparatively low temperatures. I have satisfactorily used in containers having a partial vacuum therein gaskets made of material which becomes quite plastic at from about 212° F. to 260° F. "Koroseal" is an example of a rubber substitute which has been successfully used by me as gasket material in producing sealed packages in accordance with the invention.

Moreover, the sealing action is effected without cutting or deforming the elastic material beyond its elastic limit. The same gasket therefore may be used repeatedly in different sealing operations.

Various types of glass containers, including bottles, tumblers and different kinds of jars, and various types of cap closures and gaskets other than those shown in the drawings obviously may be used in making sealed packages of the invention substantially in the manner herein particularly pointed out or in various modifications thereof which readily will occur to those skilled in the art.

I claim:

1. A sealed package comprising a glass container having an opening at the upper end thereof and provided with an external annular sealing surface on its upper end portion, below the level of and adjacent to the mouth of said opening, and with an external flange at the end of said sealing

surface remote from said mouth, said sealing surface decreasing in diameter from its end portion nearest to said mouth toward said flange, a glass closure cap having a skirt extending downwardly over the upper end portion of the container in spaced concentric relation therewith, said skirt having an internal substantially cylindrical surface located directly outward from said external sealing surface on the container, said cap having an arcuately curved inner corner surface at the upper end of said cylindrical surface, and a gasket of compressible resilient material, said gasket, when uncompressed, being rectangular in cross-section and of greater height than the vertical distance from said flange to the level of the upper end of the container, the inner diameter of said gasket being less than the diameter of the larger, upper end portion of said external annular sealing surface on the container and its outer diameter being slightly larger than that of the cylindrical sealing surface on the inner wall of the skirt of the cap, said gasket being disposed on the upper end portion of the container so as to be seated at its lower end on said flange and to be interposed mainly between said sealing surfaces and compressed thereby to a greater extent by the upper end portions of said sealing surfaces than by the lower end portions thereof, the upper end portion of the gasket extending above the level of the upper end of the container and being compressed inwardly and downwardly by said arcuately curved inner corner surface of said cap.

2. A sealed package comprising a glass container having an opening at one end thereof and provided with an external annular sealing surface adjacent to the mouth of said opening and with an external flange at the end of said sealing surface remote from said mouth, a glass closure cap for the container having a skirt surrounding the portion of the container provided with said sealing surface and with said flange in spaced concentric relation therewith, said external annular sealing surface decreasing in diameter from the end thereof nearest the level of the mouth of said opening toward said flange, the skirt of said cap having an internal sealing surface of substantially cylindrical configuration located directly outward from said first-named sealing surface, said skirt having an annular guiding surface of enlarging diameter extending from said cylindrical sealing surface toward the free edge of said skirt and surrounding said flange, and a gasket of compressible, resilient material of rectangular shape in cross-section and of greater thickness in cross-section when uncompressed than the width of the narrower portion of the space between said sealing surfaces, said gasket being disposed between said sealing surfaces so as to be seated at one end against said flange and being sufficiently longer than the distance between said flange and the level of the mouth of the container opening to extend beyond the latter so as to be compressed longitudinally between the flange and said cap and forced partially against the adjacent end surface of the container when the cap is applied.

3. A sealed package comprising a glass container having an opening at the upper end thereof and provided with an external annular flange on its upper end portion and with an external annular side sealing surface thereon above said flange, a glass closure cap having a cover portion overlying the upper end of the container and a skirt portion extending downwardly over the

upper end portion of the container in spaced concentric relation therewith to a level below that of the upper surface of the flange, said skirt having an internal annular side sealing surface located directly outward from said external side sealing surface on the container, said two side sealing surfaces being cooperatively configured to define between them an annular gasket-receiving space of decreasing width from the upper surface of said flange to a level near that of the upper end of the container, and an annular gasket of compressible, resilient material having its lower end seated on the said flange and extending upwardly in the space between said cooperatively configured side sealing surfaces to a level above that of the upper end of the container, said gasket, when uncompressed, being of rectangular shape in cross-section and having a thickness greater

5 than the width of the narrower upper portion of the space between said side sealing surfaces and a length greater than that of said space so that, on application of said cap to said container, said gasket will be compressed radially between the upper portions of said cooperative side sealing surfaces and longitudinally between said flange and the cover portion of the cap, the upper end portion of the gasket thus being forced partially between the upper end of the container and the cover portion of the cap.

10 4. A sealed package as in claim 3 wherein the cap has an arcuately curved inner corner surface engaging with the outer upper corner portion of the gasket to press the upper end portion of the gasket downwardly and inwardly against the upper end of the container.

15 WALTER K. BERTHOLD.
